DOUBLE-ACTING HYDRAULIC HOIST

Vernon I. Gandrup, Watsonville, Calif.

Application April 22, 1947, Serial No. 743,105

2 Claims. (Cl. 121—46)

1

An object of my invention is to provide a double acting hydraulic hoist which differs from the device shown in my copending application, Ser. No. 738,705, filed April 1, 1947. In my copending case, I provide a stationary cylinder and slidably mount a movable cylinder therein. I further provide a stationary hollow piston rod carried by the stationary cylinder and mount a stationary piston on the rod. The movable cylinder has a closed inner end with a sleeve for slidably receiving the rod and the piston is slidably received in the movable cylinder.

In the copending case, the return for the fluid from the stationary cylinder after the movable cylinder reaches its limit of travel is through a port in the hollow piston rod, uncovered by the sleeve of the movable cylinder. My present invention makes use of a separate passage, external of the stationary cylinder and having its inlet end uncovered when the movable cylinder is fully extended.

I also provide a novel control valve for the external passage and for other inlet and outlet pipes connecting the valve with the two cylinders, whereby a movement of the valve in one direction will cause the fluid to extend the movable cylinder and a movement of the valve in the opposite direction will cause the fluid to positively retract the movable cylinder. In addition to this the valve may be moved to an intermediate position for stopping the movable cylinder in its travel at any point desired while being extended or retracted. It is also possible to leave the valve in either of its extreme positions and when the movable cylinder reaches the end of its travel as caused by the particular position of the valve, ports will be uncovered which will permit the fluid to continue to flow to and from the cylinders, thus obviating the necessity of returning the valve to a "neutral" position when the movable cylinder reaches the end of its stroke.

The invention is simple in construction and is durable and efficient for the purpose intended.

Other objects and advantages will appear in the following specification, and the novel features of the device will be particularly pointed out in the appended claims.

My invention is illustrated in the accompanying drawing forming a part of this application, in which:

Figure 1 is a vertical section through the device, the control valve being shown in elevation;

Figure 2 is a longitudinal section through the control valve;

2

Figure 3 is a horizontal section taken along the line III—III of Figure 1;

Figure 4 is an end elevation of the control valve as seen adjacent line IV—IV of Figure 2; and

Figure 5 is a perspective view of the insert for the control valve.

While I have shown only the preferred form of my invention, it should be understood that various changes or modifications may be made within the scope of the appended claims without departing from the spirit and scope of the invention.

In carrying out my invention, I provide a stationary cylinder A that has an end plate 1 secured thereto by bolts 2 or other suitable fastening means. A movable cylinder B is slidably received in the stationary cylinder and a packing gland A1 is carried by the cylinder A and makes a liquid tight connection with the outer surface 3 of the movable cylinder B. The outer end of the cylinder B is closed by an end plate 4.

A stationary hollow piston rod C is mounted in the stationary cylinder and is axially aligned therewith. The piston rod has one end secured 25 to the end plate and the movable cylinder B has a closed inner end 5 with a sleeve 6 for slidably receiving the piston rod. A stationary piston is mounted on the free end of the piston rod and is slidably received in the movable cylinder. A liquid receiving compartment 7 is formed in the movable cylinder and is bounded by the closed end 5 and the piston D. The end plate 4 has an opening 8 therein for permitting air to enter or leave that portion of the movable cylinder B bounded by the piston D and the end plate 4.

One of the novel features of my invention in the present case and also in my copending case is the means for delivering fluid under pressure to the compartment 7 for positively retracting the movable cylinder B. This means includes the hollow piston rod as a conveyor housed within the stationary and movable cylinders for delivering fluid to and for withdrawing it from the compartment 7. The piston rod has an opening 9 communicating with the compartment 7.

By delivering fluid to and from the compartment 7 along the aligned axes of both stationary and movable cylinders, it is possible to make the cylinders of any diameter desired. The larger the diameter of the cylinders, the greater the bearing area between the outer surface 3 of the movable cylinder B and the inner contacted area 10 of the stationary cylinder A. By making the diameters of the cylinders larger, it is also possible to increase the lifting effect of the

movable cylinder B and also the retractive force of the same cylinder. Very little lateral play between the cylinders need be overcome, the cylinders themselves providing their own support against this movement.

In order to cause the movable cylinder B to be extended, the end plate 1 of cylinder A has a fluid inlet pipe 11 communicating with the interior of the stationary cylinder. The fluid trapped in the compartment 7 during the extension of the movable cylinder will pass through the opening 9 in the piston rod and enter the interior of the rod. A return fluid pipe 12 for the rod C has one end secured to the plate 1 and communicates with the interior of the rod. When the cylinder B reaches its limit of extension, a return fluid pipe 13 has its entrance end uncovered by the inner end 5 of the movable cylinder and the fluid will flow into this pipe.

I provide a novel control valve E for simultaneously opening the pipes 11 and 12 and the outlet end of the pipe 13. Before describing this valve it is best to state that the cylinder B is positively retracted by forcing fluid through the piston rod C and into the compartment 7 by means of the opening 9. A fluid inlet pipe 14 communicates with the interior of the rod C. The fluid trapped in the stationary cylinder A during the return of the cylinder B, will flow into an outlet opening 15 disposed near the base of the cylinder and then into a fluid return pipe 16. The same valve E that simultaneously opens the pipes 11, 12 and 13 when the cylinder B is extended, will open the pipes 14 and 16 and close the pipes 11, 12 and 13 when it is desired to retract the cylinder. When the cylinder B is fully retracted, an opening 17 in the cylinder wall and near the closed end 5 will register with an annular groove 17a, and an opening 17b that communicates with the pipe 16 with the result that fluid can continue to enter the compartment 7 and will leave by the fluid return pipe 16.

It is now best to describe the structure of the control valve E and then set forth the operation of the entire device. Referring to Figure 2, it will be noted that the control valve has a cylindrical housing 18. A removable insert, indicated generally at E' in perspective in Figure 5, is placed in the housing and is secured in place by cap screws 19 or other suitable fastening means. The insert E' has a central and longitudinally extending cylindrical portion 20 in which a valve body 21 is slidably mounted. The valve body has three transversely extending bores 21a, 21b and 21c. A lever 22, pivoted at 23 is used for shifting the valve body 21 along the cylindrical portion 20.

In Figure 5 I show longitudinally extending and diametrically opposed partitions 24 that are integral with the cylinder 20. Figure 4 shows the outer edges of these partitions contacting the inner surface of the valve housing 18 to form a liquid tight seal. A lower half disc partition 25 divides the lower portion of the housing 18 into an inlet fluid manifold F and an outlet fluid manifold G. A fluid inlet pipe 26 leads from a pump, not shown, to the inlet manifold F and a return fluid pipe 27 leads from the return fluid manifold G to the pump or fluid supply reservoir. The cylindrical portion 20 has a plurality of openings F1, F2 and F3 communicating with the inlet manifold F and a second group of openings G1, G2 and G3 communicating with the return manifold G. The bores 21a and 21b in the valve body 21 are spaced to register simultaneously

with the openings F1 and G1, F2 and G2, or F3 and G3.

In Figure 5 I show four upper half disc partitions 28, 29, 30 and 31 spaced from each other with the peripheries of these discs making liquid tight seals with the inner surface of the housing 18. The end plate 32 of the valve insert E' cooperates with the half partition 28, the partitions 24 and the housing 18 form a fluid outlet compartment H. An opening H' in the cylindrical portion 20 places the compartment H in communication with the inlet manifold F when the valve body bore 21a registers with the opening H' and opening F1.

A second fluid outlet compartment J is bounded by the half disc partitions 28 and 29, and an opening J' in the cylindrical portion 20 places this compartment in communication with the manifold F when the valve body 21 is shifted for bringing the bore 21a into registry with the openings J' and F3. The half disc partition 28 lies in the same plane as the lower half disc partition 25.

A fluid inlet compartment K is bounded by the half disc partitions 29 and 30, and this compartment has an opening K' in the cylindrical portion 20 that places it in communication with the outlet manifold G when the bore 21b of the valve body 21 communicates with the openings K' and G1. A second fluid inlet compartment L is bounded by the half disc partitions 30 and 31, and the compartment has an opening L' in the cylindrical portion 20 that places the compartment in communication with the manifold G when the valve body 21 is shifted to bring the bore 21b into registration with the openings L' and G3.

Still another fluid inlet compartment M is bounded by the half disc 31 and the closed end portion 33 of the housing 18, and the compartment is provided with an opening M' in the cylindrical portion 20 that places this compartment in communication with the manifold G when the bore 21c of the valve body 21 communicates with the opening M' and an opening G4, the latter communicating with the manifold G. Figure 2 shows the pipes 11, 14, 12, 16, and 13, reading from right to left, communicating with the compartments H, J, K, L and M, respectively. The pipes permit the control valve E to be disposed remote from the cylinder A and B if desired and still control the operation of the cylinder B.

The valve E has a bypass 34 whose inlet 34a and outlet 34b register with the bores 21a and 21b when the valve body 21 is shifted into an intermediate position. The bores 21a and 21b when registering with the ends of the bypass in this manner, also register with the opening F2 and G2 so that the inlet manifold F is placed in direct communication with the outlet manifold G and both are cut off from the cylinders A and B. The cylinder B will therefore remain in the position into which it has been moved.

From the foregoing description, of the various parts of the device, the operation thereof may be readily understood.

The lever 22 for the valve is shown in a position in Figures 1 and 2 for placing the inlet manifold F in communication with the outlet compartment H and the inlet compartment K in communication with the outlet manifold G. Fluid under pressure will flow through the pipes 26 and 11 to enter the cylinder A and move the cylinder B into the extended position shown in Fig-

ure 1. During the movement of the cylinder B into this extended position, the fluid in the compartment 7 will return through the piston rod C, and the pipes 12 and 27 to the pump or reservoir, not shown.

When the cylinder B reaches its limit of travel, the return pipe 13 will communicate with the interior of the cylinder and fluid will flow from the cylinder A, through the pipe 13, inlet compartment M, opening M', bore 21c, opening G4, and outlet manifold G to the return pipe 27. It is possible to stop the movement of the cylinder B at any point desired between its limits of travel by moving the valve body 21 to its intermediate position where the bores 21a and 21b will communicate with the bypass 34 that connects the inlet manifold F directly with the outlet manifold G. The bore 21c will be out of registration with the openings M' and G4.

The cylinder B can be positively retracted and the fluid will enter the compartment 7 by means of the piston rod C when the valve body 21 is shifted to cause the bore 21a to interconnect the manifold F with the compartment J and the bore 21b to interconnect the manifold G with the compartment L. Fluid will now flow from the pipe 26 to the pipe 14 and the piston rod C to enter the chamber 7 and retract the cylinder B. The trapped fluid in the cylinder A will flow out through the opening 15, pipe 16, and return through pipe 27.

When the cylinder B reaches its final return position, the opening 17 will register with the groove 17a and the fluid will enter the opening 17b which communicates with the pipe 16. The valve body 21 can be shifted into its intermediate position during the return of the cylinder B by connecting the bores 21a and 21b with the bypass 34 and the cylinder B will be stopped in its travel. The partition 31 may be dispensed with if desired and the compartments L and M combined into one. The hoist may be used as a hydraulic ram.

I claim:

1. A double acting hydraulic hoist comprising a stationary cylinder, a movable cylinder slidably mounted in the stationary cylinder, a hollow piston rod carried by the stationary cylinder, said movable cylinder having a closed end with a sleeve for slidably receiving the piston rod, a piston secured to the piston rod and being slidably received in the movable cylinder, a fluid inlet pipe communicating with the stationary cylinder for delivering fluid under pressure thereto, a return fluid pipe communicating with the interior of the piston rod, said rod having an opening communicating with the space in the mov-

able cylinder bounded by the piston and the closed end for conveying trapped fluid from this space to the hollow piston rod and return pipe, and a second return pipe communicating with the stationary cylinder at a point where the entrance to this pipe will be uncovered when the movable cylinder is fully extended, whereby fluid can continue to enter the stationary cylinder through the inlet pipe and will leave the cylinder through the second return pipe, a second fluid inlet pipe communicating with the interior of the hollow piston rod, a third fluid return pipe for the stationary cylinder, and a control valve for closing the first fluid inlet pipe and the first and second return fluid pipes and for opening the second fluid inlet pipe and the third return fluid pipe.

2. A double acting hydraulic hoist comprising a stationary cylinder, a movable cylinder slidably received in the stationary cylinder, a hollow piston rod carried by the stationary cylinder, the movable cylinder having a closed end with a sleeve for slidably receiving the rod, a stationary piston carried by the rod and being slidably received in the movable cylinder, a fluid inlet pipe for the stationary cylinder, a return fluid outlet pipe communicating with the stationary cylinder so as to be opened when the movable cylinder is fully extended, the hollow piston rod having an opening communicating with the interior of the movable cylinder bounded by the closed end and piston, a second return pipe communicating with the rod interior for receiving the trapped fluid in the movable cylinder that enters the rod, a second inlet pipe communicating with the rod interior, a third return pipe communicating with the stationary cylinder, a valve for closing the first inlet and first and second outlet pipes and for opening the second inlet and third outlet pipes for causing fluid to enter the space between the closed end and piston for returning the movable cylinder, the movable cylinder having an outlet opening communicating with the third return pipe when the cylinder is fully retracted.
